ANIMATED PULL TOY

Morris Simon, Rockaway Beach, N. Y.

Application November 30, 1946, Serial No. 713,239

4 Claims. (Cl. 46—107)

1

The present invention relates to a pull toy and refers more particularly to a toy of the type comprising a simulated animal body mounted on a wheeled platform and means for imparting motion to parts of the body, said means being driven by the motion of the wheels.

An object of the present invention is to provide a toy in the form of a dog which sits up on its hind legs and returns to squatting position periodically.

A further object is that while the dog is in a sitting up position, it shall beg; that is, wave its front paws, also open and close its mouth to simulate barking, and wag its tail.

Still another object is that the cycle of sitting up, begging, and returning to squatting position shall be spread over two revolutions of the driving wheels on which the dog is mounted, thus creating a reasonable lapse of time in each position.

Yet another object is that the mechanism for all the above motions shall be as simple as possible, and trouble free in all operations.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevation of the pull toy with the dog body in squatting position.

Fig. 2 is a similar view with the dog sitting up.

Fig. 3 is a front view of the same.

Fig. 4 is a rear view of the same.

Fig. 5 is a top plan view of the same.

Fig. 6 is an enlarged partial transverse sectional view on line 8—6 of Fig. 5.

Fig. 7 is an enlarged partial longitudinal sectional view on line 7—7 of Fig. 5.

Fig. 8 is a view similar to Fig. 7 but with the dog body in squatting position.

Fig. 9 is an enlarged bottom elevation of the toy.

Fig. 10 is a side elevation of the main pivot of the dog body.

Referring now to the figures, the toy 11, as embodied, comprises a platform 12 mounted on wheels, the front wheels 13 being fixed on a common shaft 14 by cotter pins, and the rear wheels 15 being fixed on a common shaft 16 by cotter pins.

Platform 12 has side apron members 17 formed with the slots 18 for the drive bar 19, the latter

being driven by links 20 connected to studs 21 on rear wheels 15 near the periphery thereof.

The dog body 22 comprises the simulated torso portion 23 which is mounted in standards 24 on the pivot 25. The torso portion 23 comprises integrally a simulated head portion 26 and in the latter is pivotally mounted, as at 26a, a portion 27 constituting a simulated jaw with tongue.

The jaw portion 27 is urged into closed position by a leaf spring 28. The jaw portion 27 further has a rearward extending portion 29 more fully described hereinafter.

Extending longitudinally through torso portion 23 is a rod 30, the top end of the bore for which is closed by a plug 31 in the simulated head 26.

Rod 30 is a substantially solid cylinder and comprises a hardened steel ball 32 peened into its lower end 33.

The rearwardly extending portion 29 of the jaw portion 27 is engaged on its lower side by a lip 34 formed on rod 30.

Leg portions 35 are mounted on a common pivot 36 in torso 23 and are further pivotally connected to the rod 30 by a pin 37.

25 The leg portions 35 have forepaw portions 38 loosely pivotally connected thereto.

A simulated tail portion 39 is pivotally mounted at the lower rear end of torso portion 23 and has an inwardly extending portion 40 which is engaged on its upper side by a lip 41 formed on rod 30.

Standards 24 are secured to the platform 12 by bolts 42 and the pivot 25 has a central torso engaging portion 43 and end portions 44 of reduced diameter, the latter engaging standards 24. By this construction, pivot 25 is securely retained between standards 24 which snugly fit its end portions 44, and no nuts or other fastening means are used in retaining pivot 25 in position.

40 Mounted on rear axle 16 there is a cam gear 45 which comprises four teeth 46 spaced 60 degrees from one another leaving a smooth portion 47 of cam 45 of approximately 180 degrees.

A cam follower 48 formed on a follower plate 49 engages the cam 45. The follower plate 49 is pivotally mounted on a stiff wire 50 which is mounted on the rear pair of the bolts 42 of standards 24 and below platform 12, as best seen in Fig. 9.

50 A slotted plate 51 is pivotally connected at 52 to the torso 23 and extends downward and forward from pivot 52, then straight forward for a considerable distance terminating forward in a pointed portion 53, whose upper surface 54 is even with the upper surface 55 of the body 56 of the slotted plate 51, and whose lower surface

57 slants downwardly and rearwardly from the front end at a slight inclination merging into the body 56 of the slotted plate 51, whose lower forward surface 58, is slanted upward sharply to meet it.

The slotted plate 51 is formed with the bifurcated slot 59 which comprises an upper portion 60 above its forward half portion 61. The upper portion 60 and the forward half portion 61 of the slot 59 are separated by a finger 62. A trigger 63 is mounted by a pivot 64 on the slotted plate 51 and comprises a lower arm 65 and a forward arm 66, the latter being formed with a nose 67.

A trigger bar 68 extends laterally of platform 12 between the apron members 17, parallel to axles 14 and 16 and somewhat to the rear of front axle 14.

A coil spring 69 is anchored to platform 12 as at 70, and to the lower forward portion of torso portion 23.

The operation of the toy is as follows:

With the dog body 22 in squatting position, that is, with torso 23 almost horizontal as illustrated particularly in Figs. 1 and 8, the wheels 13 and 15 are caused to revolve by pulling the toy.

The revolution of cam 45 and the movements of follower plate 49, will have no effect on the dog body 22 in the relation of parts shown in Fig. 8.

As wheels 15 revolve so that studs 21 are in a forward position, the links 20 actuate drive bar 19 forwardly and the latter enters the upper portion 60 of slot 59, since the slotted plate 51, being pivoted at its rear end on pivot 52, will assume the lowest position possible relative to the drive bar 19.

In the forward travel of drive bar 19, the slotted plate 51 is lifted from the downward slanting position of Fig. 8 to the position of Fig. 7, in which its body portion 56 is substantially horizontal and further driven forward by the forward drive of drive bar 19. At the end of the forward travel of the drive bar 19 and the slotted plate 51, the nose 67 of trigger 63 has caught on the trigger bar 68. In the course of the forward travel of slot plate 51, it has pulled pivot 52 forwardly around pivot 25, causing the dog body 22 to assume the substantially erect position of Figs. 2, 3, 4, 5, and 7. The relation of parts is, at that moment, as shown in Fig. 7, drive bar 19 being in the full line position.

As wheels 15 continue to revolve, links 20 pull drive bar 19 backwards and it travels substantially to the rear of slot 59 dropping into the main portion thereof as soon as it is deprived of the support of the finger 62.

The slotted plate 51 is prevented from returning backward by the engagement of trigger nose 67 with trigger bar 68.

As each tooth 46 engages cam follower 48, the follower plate 49 is raised around its pivot and causes rod 30 to rise. The rising of rod 30 causes the tail 39 to wag about its pivot and causes the leg portions 35 to swing around their pivot 36 in a simulation of the dog begging.

Lip 34 of rod 30 further raises the rear portion 29 of jaw portion 27, causing the latter to drop thereby loading spring 28. When a tooth 46 has passed the follower 48, the latter will drop into the space between teeth 46 permitting the follower plate 49 to drop, whereupon rod 30 will drop actuated by spring 28 which tends to close jaw portion 27 and which, acting across pivot 26 and rear portion 29, forces rod 30 downward. This causes an opposite motion of leg portion 35.

Lip 41, acting on the portion 40 of the tail 39, 75

depresses the portion 40 raising the tail 39. The jaw portion 27, leg portions 35 and the tail 39 are thus caused to reciprocate by reason of the rising and falling of the cam follower 48 as the cam 45 revolves. Such rising and falling takes place approximately between the time when the stud 21 is in its lowermost position and the time it reaches its uppermost position in its second revolution, and while the dog body 22 is erect.

As the drive bar 19 travels forward from its rearmost to its foremost position in this second cycle, it will by gravity stay in the main forward half portion 61 of slot 59 and engage the lower arm 65 of trigger 63 as shown in broken lines in Fig. 7. This will raise the forward arm portion 66 clear of the trigger bar 68 and free the weighted dog body 22 which, augmented by the pull of spring 69, will fall forward and in so doing pull slotted plate 51 rearwardly to the position of Fig. 8, at which time the operation will recommence.

It is thus evident that in the first cycle, corresponding to a revolution of rear wheel 15, dog body 22 is raised from a squatting to a sitting position and in the second cycle, corresponding to and measured by a second revolution of rear wheels 15, the toy simulates the actions of a dog opening its mouth, begging with its front paws and wagging its tail while in a sitting up or substantially erect position.

It is to be understood that the animated figure may be in the form of a dog or any other animal, bird, etc.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In a pull toy, in combination with a platform and wheels mounted on said platform, standards mounted on said platform, a simulated animal body pivotally mounted between said standards, a drive bar driven from said wheels, means connecting said drive bar to said body for raising said body from a substantially horizontal and a releasable means for holding said body in its vertical position.

2. In a pull toy, in combination with a platform, an axle and two wheels mounted on opposite ends of said axle and fixed against rotation relative thereto, standards mounted on said platform, a simulated animal body pivotally mounted in said standards, links connected to said wheels, a drive bar connected to said links, means connecting said drive bar and to said body for raising said body from a substantially horizontal to a substantially vertical position upon revolution of said wheels, and a releasable means controlled by movement of said drive bar for holding said body in its vertical position.

3. In a pull toy, in combination with a platform, an axle and two wheels mounted on opposite ends of said axle and fixed against rotation relative thereto, standards mounted on said platform, a simulated animal body transversely pivotally mounted in said standards, said body comprising movable members and a rod engaging said members and slidably longitudinally of said body, links pivotally connected at one end to said wheels,

a transverse drive for connecting the other ends of said links, a plate pivotally connected to said body and formed with a longitudinally extending slot, said slot comprising an upper portion, said plate further comprising a finger portion separating the forward portion of said upper portion from the lower portion of said slot, said drive bar extending through said slot, a trigger bar mounted laterally on said platform and a trigger pivotally mounted on said plate, said plate upon a revolution of said wheels to the forward position of said drive bar rotating said body about its pivot and raising it from a substantially horizontal to a substantially vertical position and engaging said trigger on said trigger bar to prevent subsequent rearward motion of said plate during the rearwardly driving portion of said revolution, said drive bar being upon the succeeding revolution of said wheels engaging said trigger to disengage the same from said trigger bar and allow the body to return to its horizontal position, and cam means mounted on said axle and adapted to slidably actuate said rod to move said members while said trigger is engaged on said trigger bar.

4. In a pull toy, in combination with a platform, an axle and two wheels mounted on opposite ends of said axle and fixed against rotation relative thereto, standards mounted on said platform, a simulated animal body transversely pivotally mounted in said standards, links pivotally connected at one end to said wheels, a transverse

drive bar connecting the other ends of said links, a plate pivotally connected to said body and formed with a longitudinally extending slot, said slot comprising an upper portion, said plate further comprising a finger portion separating the forward portion of said upper portion from the lower portion of said slot, said drive bar extending through said slot, a trigger bar mounted laterally on said platform and a trigger pivotally mounted on said plate, said plate upon a revolution of said wheels to the forward position of said drive bar rotating said body about its pivot and raising it from a substantially horizontal to a substantially vertical position and engaging said trigger on said trigger bar to prevent subsequent rearward motion of said plate during the rearwardly driving portion of said revolution, said drive bar being upon the succeeding revolution of said wheels engaging said trigger to disengage the same from said trigger bar and allow the body to return to its horizontal position.

MORRIS SIMON.
